UNITED STATES PATENT OFFICE.

MAX VOGEL, OF FRANKFORT-ON-THE-MAIN, GERMANY.

STAPLING-PLIERS.

1,043,883.

Specification of Letters Patent.

Patented Nov. 12, 1912.

Application filed January 5, 1912. Serial No. 669,671.

To all whom it may concern:

Be it known that I, MAX VOGEL, a subject of the Emperor of Germany, and residing at Schäfergasse 10, Frankfort - on - the - Main, 5 Germany, have invented a certain new and useful Improvement in Stapling-Pliers, of which the following is a specification.

The object of the invention is to provide a stapling-pliers which grip the articles to 10 be secured together before the staple driver is driven through the work.

With this object in view the invention consists in the especial arrangement of the springs adapted to hold the jaw of the pliers 15 in open position, which springs are secured on such places of the levers that they are not in the way if the casing containing the staples to be fed to the jaw is to be opened or otherwise is to be acted upon.

20 A further object of the invention is to secure the pliers from becoming obstructed by a staple not wholly driven out of the guide-slot, which is obtained by the arrangement of a lock device attached to or arranged in 25 the parts of the jaw of the pliers.

In the accompanying drawings Figure 1 is a side elevation, Fig. 2 a plan view, and Fig. 3 an end elevation of the jaw of the pliers. Fig. 4 is a side elevation of the jaw 30 of a modified form of the improved stapling driver, the jaw being shown in the closed position. Fig. 5 is a view corresponding to Fig. 4, the jaw being shown in locked position. Fig. 6 is a longitudinal section 35 through the pliers, the jaw parts of which are represented in Figs. 4 and 5. Fig. 7 is a side elevation of the pliers shown in Fig. 6. Fig. 8 is a section according to the line A—B of Fig. 6. Fig. 9 is a side elevation 40 of the jaw parts of a further modified stapling-pliers, parts of the levers being broken away. Fig. 10 is an elevation corresponding to Fig. 9 but the jaw parts are shown in the locked position. Fig. 11 is an elevation 45 corresponding to Fig. 9, but the jaw is represented in the closed position. Fig. 12 is a front view of the parts of the jaw shown in Fig. 9. Fig. 13 is a view of the rear end of a modified form of the staple casing. Fig. 50 14 shows the inner parts of the casing according to Fig. 13. Fig. 15 is a view of the casing according to Fig. 13 but the rear end of the casing being closed.

Referring first to the form of execution 55 shown in the Figs. 1, 2 and 3, 15 denotes the casing adapted to carry the staples,

which are fed in the known manner as for instance by the device shown in Fig. 6 or Fig. 14. The casing 15 is mounted on a pin 16 in the manner as hereinafter described 60 with respect to Fig. 6 and is loosely in engagement with the inner sides of the levers 17 and 18, respectively, formed of sheet metal and connected by the pin 16 on which they are adapted to rock together with the 65 staple casing 15. The lever 17 carries the anvil 19 and a bolt 20, rigidly mounted on the lever 18 is connected with the staple driver 21. Said driver moves in a guide-slot 22, formed in the head of the staple 70 casing or box, and to which a staple is automatically fed when the jaws of the pliers are closed. The end of the bolt 20 is screw-threaded for the provision of a nut 23 against which the driver 21 is pressed by 75 means of a spring 24 arranged between the end of the lever 18 and the driver 21. Said spring, furthermore, tends to keep the driver in its uppermost position by rocking the lever 18 as far as possible apart from 80 the casing 15. A second spring 25 connected with the anvil 19 and the lever 18 tends to keep the jaw open. Said spring 25 is fastened with its one end to a pin 26 fixed on the inner side of the lever 18 formed semi-circular in section, and is kept out of way in 85 case the casing is to be opened in order to be refilled or inspected.

In operation the papers to be fastened together as documents or the like are placed 90 between the anvil 19 and the underside of the head of the casing 15 whereupon by actuating the handle parts of the levers 17 and 18 said papers are firmly gripped by the jaw. Continued movement of the levers in 95 the same direction causes the staple driver to descend in its guide-slot pushing the foremost staple, which was fed into the slot underneath the driver when the same had taken its uppermost position, into the papers, and clenching it on the underside of 100 same, thereby fastening the papers together. In releasing the pressure upon the levers the springs 24 and 25 will bring same back into their initial position, in which the papers 105 can be drawn from the jaw. At the same time the driver releases the staples retained by the same during its movement so that the staple feeder now can feed the foremost staple into the slot and below the driver. The 110 pliers now are ready for use for the next stroke.

In the modification shown in Figs. 4 to 8 the parts of the pliers correspond to like parts of the pliers described with respect to Figs. 1 to 3 with the sole exception that the 5 bolt 20 is provided with a recess 28 the object of which, hereinafter, will be described. 10 15 denotes the staple casing. Said staple casing 15 is loosely mounted on the pin 16 by means of lugs 29 protruding from its 10 underside and embracing said pin 16 in such a manner that the casing may be rocked about the pin 16. The casing, furthermore, is U-shaped in cross-section and is provided with a removable cover 31 guided in ears 15 20 25 attached to or integral with the lateral upper edges of the casing. The cover 31 is arched as shown in Fig. 9 in such a way as to be able to take up a rod 32 carrying a spiral spring 33 which tends to push a staple 20 25 30 feeder 34 toward the head of the casing 15, said feeder engages the rod 32 by means of a sleeve 35 adapted to be displaced longitudinally on the rod 32. Fastened by rivets 36 a staple carrier 37 is mounted in the U- 25 30 35 shaped casing 15 the rearward end of which is closed by a block 38 attached to the rod 32. In order to hold said block in place a flat spring 39 is fixed to the underside of the casing and is provided with a hole 40 that 30 35 40 is engaged by a pin 41 of the block when the same closes the casing as shown in the Figs. 6 and 7. The spring 33 being compressed between said block 38 and the feeder 37 tends to feed the staples forward to the 35 40 45 head portion of the casing where an opening is arranged having an area corresponding to the size of a staple and through which the staples are fed into the slot 22 formed in said head portion. In order to refill the 40 45 50 casing it only is necessary to push the spring 39 down thereby releasing the block 38 so that by the action of the spiral spring 33 the block may be spaced apart from the rear end of the casing and may be gripped by 50 55 60 hand. The rod 32 with the feeder may then be removed from the casing as well as the cover 31, if desired, the rearward end of same abuts against the block 38 when in position and is, therefore, protected from 55 60 65 sliding out of the ears 30 by means of said block 38. In order to facilitate the refilling of the casing the side walls and the bottom of the rear end of the casing are prolonged over the end of the staple carrier 37 and 60 65 70 when the block 38 is removed the front end of the known wooden staple carrier may be inserted into the rear end of the casing where it is held in proper position with respect to the carrier 37 so that the staples 70 75 80 easily may be fed by hand from the wooden carrier to that one mounted in the casing. As already explained the foremost staple is fed by means of the feeder 34 into the guide slot 22 of the driver and just below the same. 65 70 75 80 85 90 95 100 105 110 115 120 125 130

along the slot until it is clenched upon the anvil 19. The driver then ascends while the aperture, through which the bolt 20 passes, is sliding on the bolt 20 until the driver reaches a recess 28 by which it is stopped in its motion as its aperture engages said recess 28, the pliers now are locked. In this position of the driver the aperture for the staples through which they are fed into the slot is partly closed by the lower edge of said driver preventing in such a manner the feeding of the staples. In case a further staple is to be inserted into the papers the levers first are to be closed whereby no staple can be driven into the documents as there is none in front of the driver, and then suddenly are released. The hole of the driver, now, will not be caught by the recess 28 but will freely pass over same until the nut 23 abuts against the driver. The latter in its end position has cleared the aperture for the delivery of the staples so that the foremost one, now, can be fed below the driver, which with its next downward motion pushes same into the papers to be fastened together. The operator, therefore, according to the quickness of the releasing movement of the pliers is free to lock the driver or to bring it back into its initial position. Now, in order positively to obtain said locking position the device shown in the Figs. 9, 10, 11 and 12 is arranged on the side of the head of the casing. Said device consists of a lever 50 loosely secured to the head of the casing 15 by means of a pin 51 and a slide 52 adapted to be moved longitudinally on the enlarged end 53 of the lever 50. The enlarged end 53 as well as the slide 52 are slotted and engage a pin 54 fixed to the lever 18. The slot in the slide is somewhat shorter than the slot in the enlarged end and each slot is provided with a recess 56 that in a predetermined position of the slide on the lever register with each other. A spring 55 tends to rock the lever 50 in such a way that the pin 54 is in perpetual engagement with that side of both slots in which the recesses are located. In consequence thereof the pin engages the recesses 56 in case both should register. As shown in Fig. 9 in open position of the pliers the pin 54 abuts the upper end of the slot in the slide and of the enlarged end 53 and both recesses 56 register with each other. In closing the pliers or in imparting a downward movement to the driver the pin 54 moves along the slots and is caught by the registering recesses so that the movement of the driver is stopped while the levers are locked against retrograde movement. In consequence thereof the aperture through which the staples are fed into the guide slot remains closed and an introduction of a further staple into the guide-slot is positively prevented. In case 130

the driver could return in its initial position without having pushed the staple in front of it out of the guide the introduction aperture would be cleared a second time and a second staple would be allowed to enter the guide slot now containing two staples which obstruct the guide. This disadvantage is dispensed with if the driver be allowed to return in its original position but after it has done its full stroke and has driven out of the guide the staple contained therein. After the pin 54 has been caught in the recess 56 the levers can yet be closed farther until the pin 54 strikes the end of the slot 15 in the slide, which on continuous closing movement pushes the slide downward, so that the two recesses come out of register. The pliers being closed the pin 54 abuts the lower end of the slot in the enlarged end of the lever 50 while the upper end of said slot is now covered by the slide. In releasing the levers the springs 24 and 25 will bring same in the open position, the pin 54, during said movement, passes over the recesses as they do not register with each other and pushes the slide back into its original position, in which the recesses 56 register. At the same time the introduction opening in the casing is cleared from the driver and 30 a fresh staple can be fed into the guide-slot below the driver. The pliers now are ready for use for the next stroke.

In the Figs. 13, 14 and 15 a modified form of the casing is shown. The casing 60 which is hinged to the pin 16 as hereinbefore described is provided with a cover 61 adapted to be slipped below the ears 62 attached to or formed integral with the side walls of the casing. The latter contains the staple carrier 63 constructed somewhat shorter in length than the casing, the rear end of which protrudes over the carrier for the purpose as set forth hereinbefore. At the rear end of the casing each side wall is slotted as indicated by 64 for the insertion of a two armed lever 65, having rounded ends, fixed on a rod 66 which is engaged by the sleeve 67 of the staple feeder 68. The latter embraces the staple carrier 63 on three sides and is pushed toward the head of the casing by a spring 69 coiled upon the rod 66. Loosely mounted on the rod is a plate 70 of such dimensions as to close the rear end of the casing if brought into the position shown in Fig. 15. On said plate 70 a lug 71 is arranged and adapted to act upon the lever 65 in case the latter is put close to the plate 70. On the lever 65 a lug 72 or a pin is provided which engages a corresponding aperture 73 in the plate 70 if the lever is brought to register with same, as represented in Fig. 15.

In operation after the staples had been fed to the carrier 63 the feeder 68 is put on same and then by the engagement of the rod 66 carrying the spring 69 with the

sleeve 67 the rod is pushed into the casing pressing the spring 69 together between the feeder abutting the rearmost staple and the plate 70. Said plate is then inserted into the rear open end of the casing which is closed by said plate. In this position the two armed lever 65 abuts against the plate and by a suitable rotation of the rod 66 by means of the knob preferably attached to its end the outermost parts of the two arms engage the corresponding slots 64 so that the plate 70 is firmly held in position and cannot be pushed out of the casing. The two armed lever 65 is secured from rotation by the pin 72 engaging the aperture 73 in the plate 70 and by the lug 71 which one arm of the lever lies against. In order to open the casing it is only necessary to rotate the lever 65 in the reverse direction so that its arms clear the slots 64 whereupon the rod 66 with the feeder 68 may then be removed from the casing.

What I claim is:—

1. In stapling pliers the combination of lever handles, a staple casing hinged to said handles, a feeding device in said casing, a staple driver arranged in the head of the casing, a rod attached to one of the handles and adapted to actuate said driver, an anvil connected to the other handle, a spring 95 coiled on the rod and a second spring stretched out between the anvil and the adjacent part of the handle to which the driver is connected.

2. In stapling pliers, the combination of 100 spring controlled lever handles, a staple casing hinged thereto, a staple driver connected to one of the handles, an aperture in the driver, a connecting rod provided on said one of the handles and passing through 105 said aperture, and a recess on said rod adapted to be engaged by the driver and to lock the same.

3. In stapling pliers, the combination of 110 spring controlled lever handles, a staple casing hinged thereto, a driver mounted in the head of the casing, a lever secured to said casing head, a slide on said lever, and a pin fastened to one of the handles and engaging the lever and the slide.

4. In stapling pliers, the combination of 120 spring controlled lever handles, a casing, a lever hinged thereto, a slot in said lever, a slide adapted to be moved over said slot, an aperture in said slide, and a pin fastened to one of the handles and engaging said slot and said aperture.

5. In stapling pliers, the combination of 125 spring controlled handles, a casing, a lever hinged thereto, a slot in said lever, a slide movable on said lever, an aperture in the slide, a recess in said slot, and a corresponding recess in said aperture, a pin fastened to one of the handles and adapted to engage the said recesses, and a spring secured to the 130

- lever and adapted to keep the same in engagement with the one side of said pin.
6. In stapling pliers, the combination of spring controlled lever handles, a casing hinged thereto, a feeding device for the staples, a staple driver, and a locking device, comprising a spring actuated lever hinged to the casing, a slide on the same and a pin engaging the said lever and slide.
- 10 7. In stapling pliers, the combination of spring controlled lever handles, a casing hinged thereto, a staple driver guided in the head of the casing, a spring pressed feeder in the casing, a guide rod for same, a closure-plate adapted to be inserted into the rear end of the casing and movably secured to the guide rod, a lever fastened to said guide rod, and slots in the rear end of the side walls of the casing adapted to be engaged by said lever.
- 15 8. In stapling pliers, the combination of spring controlled lever handles, a staple casing hinged to same, a spring pressed feeder in the casing, a plate for closing the rear end of the casing, a two armed lever adapted to lock the plate in the closing position, and means for securing said lever to said plate when the latter is in the closing position.
- 20 9. In stapling pliers, the combination of manually operable levers, one of said levers having an anvil, a staple container pivotally mounted on said levers, a staple driver slidably mounted in said casing, and means rigidly carried by the other of said levers and slidably connected with said driver, substantially as described.
10. In stapling pliers, the combination of pivotally connected levers, one of said levers having a jawlike anvil, a staple container pivotally mounted on said levers and projecting abreast of the anvil to form therewith a coacting jawlike member between which the material to be stapled is inserted, and mechanism operated by the other of said levers for driving a staple, substantially as described.
11. In stapling pliers, the combination with manually operable levers and a staple casing, means operatively connecting the levers and the casing, and mechanism operated upon movement of the levers for driving a staple from said casing, substantially as described.
12. In stapling pliers, the combination with lever handles, a staple casing movably mounted thereon, driver mechanism actuated by one of the handles for driving a staple, and a locking device for locking said handles in predetermined relation, substantially as described.
